FIG. 1

FIG. 2

FIG. 3

FIG. 4

FIG. 5

FIG. 6

FIG. 1 is a perspective view of a tire showing one embodiment of our new design, it being understood that the full line portion of the design is repeated throughout the circumference of the tire, the opposite side being substantially the same as that shown;

FIG. 2 is an enlarged cross-sectional view thereof taken on line 2—2 of FIG. 1;

FIG. 3 is a perspective view of a tire similar to FIG. 1 showing another embodiment of our new design;

FIG. 4 is an enlarged cross-sectional view taken on line 4—4 of FIG. 3;

FIG. 5 is a plan view of a portion of the tire shown in FIGS. 1 and 2; and

FIG. 6 is a plan view of a portion of the tire shown in FIGS. 3 and 4.

The dominant features of the design reside in the portions shown in full lines in the drawings.

We claim:

The ornamental design for a tire, substantially as shown and described.
